UNITED STATES PATENT OFFICE.

JOSEPH KEEFE, OF BOSTON, MASSACHUSETTS, ASSIGNOR TO THE ZEE SOCKET AND MANUFACTURING COMPANY, OF BOSTON, MASSACHUSETTS, A CORPORATION OF MASSACHUSETTS.

SOCKET-SHELL.

1,175,528.

Specification of Letters Patent. Patented Mar. 14, 1916.

Application filed August 23, 1912. Serial No. 716,623.

To all whom it may concern:

Be it known that I, JOSEPH KEEFE, a citizen of the United States, and a resident of Boston, in the county of Suffolk and State 5 of Massachusetts, have invented certain new and useful Improvements in Socket-Shells, of which the following is a specification, taken in connection with the accompanying drawing, which forms a part of the same.

10 My invention relates to casings for electrical apparatus.

More particularly it relates to socket shells and to removable insulating linings for the caps of such socket shells which are 5 located within the caps without bending or otherwise marring any portion of the insulating lining and there preferably secured by a removable ring. Preferably this ring has relative movement with relation to the 10 cap for a purpose to be hereinafter described.

My invention further relates to the locking means to secure the cap and shell of the socket together, and more particularly to 25 means for holding the screws or other longitudinally extending locking members to the shell to prevent their accidental disengagement.

In the accompanying drawing showing 30 illustrative embodiments of my invention, and in which the same reference numerals refer to similar parts in the several figures.—Figure 1 is a vertical longitudinal section of an electric light socket equipped 35 with my invention, a husk with which it is sometimes used being also shown in section; Fig. 2 is a transverse vertical section substantially on the line 2—2 of Fig. 1 looking in the direction of the arrows; Fig. 3 is a 40 horizontal section on the line 3—3 of Fig. 1, the husk being omitted; Fig. 4 is a fragmentary side elevation of the shell showing the preferred form of means to hold the screw in its proper position; Fig. 5 is a 45 detail sectional view on the line 5—5 of Fig. 4; Fig. 6 is a perspective view of the revoluble ring; Fig. 7 is a side elevation, partly broken away, of one form of my invention, showing the ears of the ring co- 50 operating with notches in the insulating base, which is the preferred construction; Fig. 8 is a perspective view of the removable insulating lining; Fig. 9 is a fragmentary side elevation showing a modified form 55 of wedge; Fig. 10 is a fragmentary side

elevation of a further modification showing a different form of wedge member; and Fig. 11 is a detail fragmentary sectional view on the line 11—11 of Fig. 4.

It has been old prior to my invention to 60 use insulating linings for the cap of electric light socket shells which were held within the cap simply by frictional contact with its interior surface. It has also been old prior to my invention to use a removable insulating lining for the cap of socket shells which was held within the cap by some locking or fastening mechanism on the interior of the cap, the insulating member, or some portion of it, being sprung or bent to pass over 65 some obstruction or projection, reliance being placed upon the insulating member again springing out into its original condition to coöperate with the interior projections so as to prevent the insulating lining 70 from falling out of the cap. These insulating linings are usually made of fiber, as is well known in the art, and are usually cut away to form notches or other surfaces to coöperate with shoulders or surfaces within 75 the cap.

In practice, immense numbers of electric light sockets and their casings are sold to manufacturers of electric fixtures to be assembled with the other portions of the fixtures made, or assembled, by such manufacturers. It is frequently necessary for such manufacturers to refinish or replace the socket casing, including the cap, to match or harmonize with the particular electric 80 fixture of which it is to be a part. Before such replating or refinishing, however, it is necessary to remove the insulating lining from the socket shell. The lower fiber lining or insulating lining, which insulates 85 the shell portion of the socket, readily slips out of the shell so that its removal does not mar it or require any particular care. The removal of the lining from the cap, however, is quite a delicate operation, for the lining 90 has to be pried off or otherwise removed from the interior locking mechanism, mounted on the interior of the cap, and which coöperates with the notches, fingers, or other portions of the insulating lining, 95 to hold it in its position within the cap. This frequently mars the insulating lining. The frequency and extent of the damage to the lining depends upon the labor employed for this purpose. Usually unskilled labor is 100 105 110

employed with the result that large numbers of the insulating linings have been either ruined by being removed from the interior locking surfaces in the cap, or have been so torn or marred that when they were again placed in the cap, after it has been replated or refinished, it was liable not to retain its position and the tears or cracks in the lining caused by its removal and repositioning would often defeat the very purpose of providing the cap with an insulation to prevent it from becoming electrified with possible damage to the fixture or shock to the person who may be handling it after the fixture has been installed. Often the interior insulating lining was so torn or marred that it could not be placed back in the cap and consequently either a new lining had to be substituted or, if one was not at hand, the manufacture of the entire electric light socket, or the entire fixture of which it was to form a part would have to be delayed until a new lining could be obtained. In some cases where unskilled labor was employed and speed in re-assembling the sockets after replating was demanded by the employer, no lining would be placed in some of the sockets. It has been further found that where screws extending longitudinally of the socket are used to hold the cap and socket together, that it requires considerable dexterity to lock the parts together, for the reason that the screws are apt to fall out of the shell, particularly if the shell is adjusted vertically to the cap which is the usual form of adjustment. This is particularly true when the socket is used in connection with a husk, it being well known in the trade that the cap is first used to position the husk.

By my invention I avoid bending or otherwise marring the insulating lining which is substantially rigid and formed of substantially heavy fiber, porcelain, or any other suitable insulating material for it does not have to yield or bend to be sprung over any projection to hold it within the cap.

My invention further permits the locking screws to be held to the shell after being once positioned even though the shell is subjected to comparatively rough usage. By my invention, moreover, the cap can be first secured to a bracket (to hold a husk or other member) and then the rotatable ring can be moved around to any suitable position to operate with the screws and still permit the socket key to extend through the opening in the husk.

In the illustrative embodiments of my invention shown in the drawing, 1 is the removable insulating lining formed of any suitable insulating material, preferably unbendable fiber, or porcelain, or some other insulating material. This removable ring 65 for the cap is preferably substantially hat

shape having a crown 2 and a brim 3, the latter being preferably notched at 4, 4 to permit the free passage of the longitudinally extending screws 5, 5. The brim is provided in any suitable manner with an 70 upwardly extending projection or wedge 6. This wedge may be riveted to the brim as shown in Fig. 1, or it may be molded in the rim 7 of the insulating member 8, so as to form a rigid hollow enlargement 9, or it 75 may be cast solid as 10 in the insulating lining 11, Fig. 10. This enlargement or wedge member, however it is formed, cooperates with the jaws 12, 12 of the split revoluble ring 13, Fig. 6. This ring is provided with outwardly extending fingers 14, 14 which are tapped and are rotatably mounted in an interior groove 15, spun, or otherwise formed, in the cap 16 of the electric light socket 17.

The shell 18 is provided with the usual enlargement 19 which is provided with openings 20, 20 for the reception of the longitudinally extending locking screws 5, 5 which extend up through the interior of the shell 18, their upper ends being formed with screw threads 21 to coöperate with the threads in the ears 14, 14 of the revoluble ring 13. By bringing the ring 13 into proper position so that the ears 14, 14 will coöperate with the screws 5, 5, it is obvious that by simply screwing up on these screws 5, 5 the shell 18 will be securely held to the cap 16 and in this manner the two parts of the electric light socket shell 17 will be secured together. If the electric light socket is used with a husk 22, as is frequently done, though, of course, it will be understood that my socket is adapted to be used without a husk, the cap 16 is employed to secure the 95 husk to the fixture 23 in the usual practice. Should the opening in the husk (not shown) for the key 24 be in such a position, after the cap and husk are secured to the fixture 23 as not to permit the ends of the screws 5 to register with the ears 14, 14 so as to lock the cap and shell together, it is merely necessary to rotate the ring 13 by the finger or a screw driver, or other similar instrument, until the ears are 100 made to assume a position to coöperate with the screws 5, 5, when the parts can be immediately secured together by tightening up the screws 5, 5. The friction of the ring 13 in the groove 15, after the screws 5, 5 have 105 been properly screwed up, is sufficient to prevent relative movement between the cap 16 and the shell 18.

It is, of course, to be understood that the removable insulating lining 1 moves with the removable ring 13 and that both the ring 13 and the lining can be immediately removed for replating or refinishing of the cap, and again positioned after refinishing without bending or otherwise marring the 110

insulating lining which, when repositioned in the cap, is in the same condition as when originally applied.

Another feature of my invention is to provide yielding means to prevent the accidental disengagement of the screws from the shell. One form of my invention is to provide the shell 18 with a groove 25 formed by bending in a portion of the shell. This bent in portion of the shell yieldingly engages the upper portion of the screws 5, 5. The upper portion 26 of the bent in part of the shell also co-operates with the lowest screw thread on the screws and prevents the accidental or unauthorized withdrawal of the screws from the shell. In fact considerable pressure on the end of the screw is required to force the screw threads past the bent in portion 25. This insures the screws retaining their position on the shell after once being assembled without the annoyance of having them drop away from the shell or becoming otherwise lost or misplaced. I also preferably bend the insulating lining 27 of the shell 18 forming it with the vertical groove 28 which serves also to present a more or less yielding pressure on a portion of the screws 5, 5 and tends to keep them in their position within the shell. The friction of the bent in portion 25 of the shell, however, will itself, without any aid from the insulating lining, prevent the screws from dropping out, though the insulating lining may be used as an additional precaution, either with or without the bent in portion 25 of the shell.

The insulating base 29 is provided with vertical grooves to receive the inwardly extending ridges 30 formed by bending in the insulating lining 27 to accommodate the locking screws 5, 5. In the preferred construction, the insulating base 31, is in all respects similar to the insulating base 29, except that the longitudinally extending grooves 32 for the reception of the inwardly extending ridges 30, 30 of the insulating lining 17, are extended up to form shoulders 33, 33 between which the ears 14, 14 of the ring are received. In this preferred construction after positioning the insulating member 31, so that the ears 14, 14 are received in the longitudinal grooves 32, there can be no relative movement between the ring 13 and the insulating base 31. In this form the brim 3 of the insulating lining 1 and the ring 13 are received in the depressed or cut out portion 34 in the top of the insulating base 31.

Having thus described this invention in connection with several illustrative embodiments thereof to the details of which I do not desire to be limited, what is claimed as new and what it is desired to secure by Letters Patent is set forth in the appended claims:

1. In a cap for a socket shell the combination of a rigid insulating lining and a split ring to secure the rigid insulating lining to the cap and means carried by the insulating lining and held by the ring between the ends of the latter to secure the lining and ring together. 70

2. In a cap for a socket shell, the combination of a rigid insulating lining and a split ring to secure the rigid insulating lining to the cap, and expanding means carried by the insulating lining to expand the ring. 75

3. In a cap for a socket shell the combination of a removable rigid insulating lining and a removable split ring to secure the rigid insulating lining to the cap and a projection carried by the insulating lining and held by the ring between the ends of the latter to secure the lining and ring together. 80

4. In a cap for a socket shell, the combination of a removable rigid insulating lining and a removable split ring to secure the rigid insulating lining to the cap, and expanding means carried by the insulating lining to expand the ring. 85

5. In a cap for a socket shell, the combination of a cap provided with a circumferential groove, a rigid removable insulating lining, a removable split ring, and means carried by the ring to co-operate with the groove and means carried by the ring to co-operate with the rigid insulating lining. 95

6. In a socket shell, the combination of a shell, a cap, and longitudinally extending rotative locking means to secure the cap and shell together, and means to prevent the longitudinally extending locking means from accidentally becoming disassociated from the shell. 100

7. In a socket shell, the combination of longitudinally extending locking screws to hold the cap and shell together and means independent of the threading of said screws to removably hold the screws to the shell. 105

8. In a socket shell, the combination of longitudinally extending locking screws to hold the cap and shell together, and yielding means to removably hold the screws to the shell. 110

9. In a socket shell, the combination of a longitudinally extending locking screw to hold the cap and shell together, and a shell provided with an indentation to frictionally engage the screw to prevent its accidental withdrawal from the shell. 115

10. In a socket shell, the combination of a longitudinally extending locking screw to hold the cap and shell together, and a shell provided with an indentation, the upper surface of which co-operates with the lower thread of the screw to prevent the accidental withdrawal of the latter from the shell. 125

11. In a socket shell, the combination of a longitudinally extending locking screw to hold the cap and shell together, and a shell 130

provided with an indentation and with an insulating lining, both of which frictionally engage the screw to prevent its accidental withdrawal from the shell.

- 5 12. In an electric light socket the combination of a cap provided with a circumferential groove, a split ring having ears to be received in the circumferential groove, a rigid insulating lining for the cap, co-operating means carried by the ring and lining to

secure the lining to the split ring, longitudinally extending locking screws to lock the cap and shell together, and an insulating base portion having longitudinal grooves to receive said locking screws and the ears of 15 the ring.
